BY

INVENTOR.

HUGH J. BAKER,

ATTORNEY.

UNITED STATES PATENT OFFICE.

HUGH J. BAKER, OF INDIANAPOLIS, INDIANA.

REMOVABLE FORM FOR ORNAMENTAL CONCRETE.

Application filed June 6, 1925. Serial No. 35,305.

To all whom it may concern:

Be it known that I, HUGH J. BAKER, a citizen of the United States, residing at Indianapolis, in the county of Marion and 5 State of Indiana, have invented a new and useful Removable Form for Ornamental Concrete, of which the following is a specification.

It is the object of my invention to produce collapsible and removable forms for 10 molding in place ribbed-slab concrete floors with ornamental ceilings.

Heretofore, for a number of years, ribbed-slab concrete floors have been molded in 15 place with non-ornamental ceilings, by the use of collapsible and removable forms. However, when it was desired that the ceilings of such concrete floors be ornamental, it has heretofore been necessary to apply the 20 ornamentation manually after the original concrete has set sufficiently to permit removal of the collapsible forms which provided the non-ornamental ceilings; usually by first applying a metal-lath drop ceiling 25 and then either applying precast plaster ornamental strips to such drop ceiling or else applying plaster in plastic form to such drop ceiling and shaping it as desired.

By my present invention, it becomes unnecessary either to use a drop ceiling or precast strips or to apply ornamentation by 30 manual labor; for the ornamentation may be made by my forms by the original casting of the concrete in place, so that such ornamentation is complete and finished when the 35 forms are removed.

In carrying out my invention, I make the forms of a number of separate parts, some for forming the faces of the joists and 40 some for forming the floor-slabs between joists, as well as parts for forming the faces of the girders; and provide some or all of these parts, and especially the parts for forming the joist faces and the floor-slabs, 45 with various raised or depressed portions arranged to provide any desired pattern in the face of the concrete; which raised and depressed portions are suitably arranged with respect to the movements which the 50 parts of the forms must have in their removal so that such removal will not only not be interfered with but will be possible without destroying the ornamental pattern formed in the face of the concrete.

55 The accompanying drawings illustrate my

invention: Fig. 1 is a vertical section through a ribbed-slab concrete floor, taken perpendicularly to the line of the joists, and through the forms embodying my invention and by which such concrete floor may be cast in place with ornamental ceilings; Fig. 2 is a sectional perspective view, looking obliquely upward from below, showing a fragment of a ribbed-slab concrete floor having ornamental ceilings and cast in place on forms in accordance with my invention; Fig. 3 is a fragmental perspective view, looking obliquely downward from above, of the forms by which the floor of Fig. 2 is cast; Fig. 4 is a view, on a somewhat smaller scale, 60 of one unit of the forms embodying my invention, with the corner moldings and the lids omitted to show the spacing members; and Fig. 5 is a transverse section through a complete unit of which parts is shown in 65 Fig. 4.

In the construction of ribbed-slab concrete floors in buildings, there is usually a flat floor 10 which is crossed on its under side by parallel joists 11 extending in one direction, which joists rest on and spring from parallel beams or girders 12 or masonry walls extending in a direction transverse to the joists. The girders are usually heavier and deeper than the joists, and have side 80 faces 13 which sometimes flare obliquely upward to make the girder wider at the top than at the bottom, from which side faces 13 the joists 11 spring. When such obliqueness is provided, it usually does not extend 85 farther downward than the bottoms of the joists. The under faces 14 of the floor slabs extend between adjacent side faces 15 of adjacent joists 11 and between adjacent faces 13 of adjacent beams 12.

By my invention I make it possible to 90 make the faces 13, 14, and 15 ornamental by the action of the collapsible and removable forms themselves as the floor is cast in place as a monolith.

Each beam or girder 12, as shown, has a lower substantially rectangular portion the bottom and side faces of which are produced by forms-parts 20 and 21, which may be supported in any usual or convenient manner 105 forming no part of the present invention. Boards 22 may rest upon the upper edges of the beam sides 21 and project outward therefrom to constitute the forms parts for the horizontal under faces 23 which are shown 110

as extending between the bottoms of the oblique portions of the girder faces 13 and the vertical side faces of the lower parts of the girders, as it is usually desirable to provide such under faces 23. The girder forms co-operate with, and by applied joist-beams 24 help to support, the units now to be described.

These units extend from one girder form 10 to the next. Each of these units includes a lid 25, for forming the face 14, two spaced upright parts 26 for forming adjacent side faces 15 of adjacent joists 11, and two soffit pieces 27 projecting outward oppositely 15 from the bases of the two upright parts 26. The soffit pieces 27 are nailed to the upright parts 26 of the units. The soffit pieces 27 of adjacent units abut, as is clear from Fig. 3; and are desirably notched on their free 20 edges to permit the extension through them of supporting shores 28 up to the level of their top faces, so that such shores 28 may remain in place to support the joists for a time after the remainder of the forms have 25 been removed.

The supporting shores 28 furnish the main support for the units. To this end, they desirably have scabs 29 nailed on their faces, and wooden joists 30 extending transversely to the units are supported on these scabs 29 and bear against the sides of the shores 28 to furnish the supports on which the units directly rest.

The upright parts 26 on their free faces—35 the faces which are not to be engaged by the concrete—are provided with upright cleats 31, which stiffen these upright parts and join together the several boards thereof if they are made of more than one board each. 40 Nailed to the upright cleats 31 are longitudinally extending strips 32 and 33, near the bottom and top respectively; which strips are thus spaced from the boards 26 by the cleats. Spacers 34 may rest on the strips 32 to space apart by the proper distance the two uprights 26 of a unit.

The upper ends of the upright cleats 31, which may conveniently be beveled, carry strips of molding 36 which are nailed thereto and thus form rigid continuations of the side boards 26. The moldings 36 may be of a suitable shape to give the desired ornamentation to the corner between the faces 14 and 15, as is indicated generally by the ornamental portion 37 in Fig. 2. The parts 26, 27, 31, 32, 33, and 36 at one side of any unit are desirably all nailed together to form in effect a single piece.

On the two such pieces constituting the 60 sides of a unit, the lid 25 rests. This lid may be made of any desired number of boards, fastened together by cross-cleats 38, which also serve to strengthen and stiffen the lids. Some or all of these cleats 38 may have 65 slightly shorter cleats 39 attached to them,

so that the cleats 38 and 39 together serve to position the lid accurately by co-operation with the strips 33, in which case the ends of the cleats 39 abut against the strips 33, and the ends of the cleats 38 overlie such strips, as is clear from Figs. 1 and 5.

The lid 25 desirably overlies the upper edges of the moldings 36. The edges and upper face of the lid 25 may be provided with ornamentation of any suitable character which does not prevent the removal of such lid from the concrete; as by having molding 40 of suitable drawable shape nailed in the desired pattern to such top face. As shown, the molding 40 is in cross-section a 80 circular segment of something less than half a circle, for facilitating drawing from the formed concrete. For the same reason, the molding 36 is made without any undercut portions, so that it may be withdrawn 85 from the formed concrete by movement of the side parts of the units downward and away from the joists.

The ends of the units may be oblique, to conform to the oblique faces 13 of the beams 90 or girders 12. To this end, each unit has two ends parts 45, which rest upon the oblique ends of the side boards 26, and may be provided with vertical cross-cleats 46. While the tops of the oblique end-parts 45 95 need not be at a less height than the bottom of the lid 25, as when the design formed by the molding 36 is to fade away into the oblique faces 13 of the girders, yet it may stop at the height of the upper edges of the side 100 boards 26, to permit end-moldings 47 corresponding in general with the moldings 36 to be used to carry the ornamental corners 37 across the ends of the panels between adjacent joists 11, as is indicated in Figs. 2 and 105 3. The moldings 47 may be rigidly attached to the end part 45 and form part thereof.

In use, the forms are assembled as shown in Fig. 3. The girder forms 20 and 21 are 110 mounted on suitable supports. The shores 28 are set up, and the wooden joists 30 are placed on the scabs 29 nailed to such posts. The soffit pieces 27 and upright boards 26 of the various units are set in place, with the parts 27 of adjacent units abutting, and with the boards 26 of each unit spaced apart by the spacers 34. With the boards 26 the moldings 36 rigid therewith are put in place. Then the end-parts 45 with the end moldings 115 47 are laid on the oblique ends of the boards 26. Finally the lids 25 are laid in place to close the tops of the units, and located in proper position thereon by the cleats 38 and 39.

When the forms are thus erected, the concrete 10 of the floor is poured, to fill the upwardly opening spaces in the forms up to the desired level of the floor surface. The reinforcement usually provided in the con- 120 125 130

crete is not illustrated in Fig. 1, as that may be of any suitable kind and constitutes no part of this invention.

When the concrete is sufficiently set, the forms are removed from beneath it. This is done without disturbing the ornamentation which has been formed in its under surface. In this removal, the wooden joists 30 are taken down, after knocking off the scabs 29 if necessary, and the spacers 34 are taken out; then the parts of each unit are successively taken down, leaving the lid 25 until the last. In taking down the units, the upright parts 26 have their lower ends 15 swung toward each other, carrying with them the soffit pieces 27, which can be done without disturbing the ornamentation formed by the molding 36. This frees such uprights 26 and the moldings 36 from their 20 working position. Then the end-parts 45 are swung downward out of position. This may also carry down with it the end-moldings 47 if they are provided. This clears the way for removing the lid 25, which is 25 pulled loose from the concrete and lowered. All this may be done while the shores 28 are still in place to support the joists 11 while the setting of the concrete proceeds; and these shores are removed some time later.

30 In removing the forms, the ornamentation is such that the movements of the various form-parts may be obtained without marring such ornamentation. In other words, all the forms-parts, including the ornamentation-forming members thereof, are made

so that they will "draw" from the concrete. This makes it possible to produce ornamental ceiling faces of monolithic ribbed-slab floors molded in place.

I claim as my invention:

1. Removable forms for concrete floor-slab constructions of the joist type, comprising units each of which includes uprights for forming joist faces and lids for forming the ceiling faces between joists and end parts, 45 said uprights, lids, and end parts being separable, and some or all of said forms-parts being provided with ornamentation-forming portions so shaped that they permit the forms-parts to be withdrawn from the 50 concrete as they are removed without disturbing the ornamentation produced in the concrete.

2. Removable forms as set forth in claim 1, with the addition that said uprights are oblique at the ends and that said end-parts rest on the oblique ends of said uprights, which end-parts also include ornamentation-forming portions of such shape that they may be withdrawn from the concrete without mutilating the ornamentation.

3. Removable forms as set forth in claim 1, with the addition that said uprights are oblique at the ends and that said end-parts rest on the oblique ends of said uprights.

In witness whereof, I have hereunto set my hand at Indianapolis, Indiana, this 28th day of May, A. D. one thousand nine hundred and twenty-five.

HUGH J. BAKER.
